WINDOW GUARD

Miles S. McDowell, Lexington, Ky.

Application November 23, 1942, Serial No. 466,646

4 Claims. (Cl. 160—172)

The present invention relates to new and useful improvements in window guards, and has for one of its important objects to provide, in a manner as hereinafter set forth, a device of this character which is also adapted to function as a Venetian blind, said device including ladder supported tiltable slats which are adapted to be raised and lowered.

Another very important object of the invention is to provide a window guard of the aforementioned character comprising novel means for positively locking the slats in lowered position.

Other objects of the invention are to provide a window guard of the character described which will be comparatively simple in construction, strong, durable, highly efficient and reliable in use, compact, inconspicuous and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a window guard constructed in accordance with the present invention, showing the device installed.

Figure 2 is a vertical sectional view, taken substantially on the line 2—2 of Figure 1.

Figure 3 is a view in vertical section through one side portion of the device, taken at right angles to Figure 2.

Figure 4 is a view in horizontal section through the lower portion of the device with the upper section of the housing removed, showing the locking mechanism in inoperative position.

Figure 5 is a view in horizontal section substantially similar to Figure 4, but showing the locking mechanism in operative position.

Figure 6 is a plan view of one of the slats which is adapted to be secured against raising.

Figure 7 is a detail view in side elevation of the operating lever of the locking mechanism.

Referring now to the drawings in detail, it will be seen that the embodiment of the invention which has been illustrated comprises a substantially rectangular frame 1 of suitable material which is adapted to be mounted in a conventional window frame 2 inwardly of the usual sashes 3. The frame 1 includes a substantially flat metallic housing 4 which is mounted on the stool 5 of the window. Rising from the end portions of the housing 4 is a pair of substantially channel-

shaped side bars 6. The frame 1 further includes a top bar 7.

Mounted in the side portions of the frame 1 are pairs of vertical guides 8 which are spaced from each other in a manner to define slots 9. Journalized in suitable bearings 10 which are provided therefor in the upper portion of the frame 1 is a rockable tilt bar 11. Tape ladders 12 are suspended from the bar 11. A bottom bar 13 is secured to the lower ends of the ladders 12. Slats 14 are mounted in the ladders 12.

Projecting longitudinally from at least one of the slats 14, also from the bottom bar 13, are shafts 15 which are operable in the slots 9. At 15 inwardly spaced points from their outer ends the shafts 15 have fixed thereon collars 16. Projecting in opposite directions from the collars 16 are spindles 17. Rollers 18 are journalized on the spindles 17 and travel on the outer sides of the guides 8. Any suitable means may be provided for tilting and raising or lowering the slats 14, et cetera.

Also journalized in the side portions of the frame 1, outwardly of the guides 8, are vertical shafts 19. The shafts 19 have fixed thereon pairs of vertically spaced, arcuate fingers 20 for receiving the outer end portions of the shafts 15 therebetween. Arms 21 are fixed on the lower end portions of the shafts 19.

30 Pivotedly mounted at 22 for swinging movement in a horizontal plane in the housing 4 at an intermediate point is a manually operable lever 23. A longitudinal slot 24 in the front of the housing 4 accommodates the lever 23. The lever 23 includes a hinged handle 25 on its outer end. The inner end of the lever 23 is connected to the arms 21 for rocking the vertical shafts 19 through the medium of rods 26, said rods including turnbuckles 27 for adjustment.

40 Fixed on the inner portion of the lever 23 is a hook 28. The hook 28 is engageable with the bolt 29 of a key operated lock 30 in the housing 4 for securing the fingers 20 in operative position, 45 as illustrated to advantage in Figure 5 of the drawings.

It is thought that the operation of the device will be readily apparent from a consideration of the foregoing. Briefly, with the hand lever 23 extending at right angles from the housing 4, as seen in Figure 4 of the drawings, the fingers 20 are out of the path of the shafts 15 and the slats 14 may be freely raised or lowered as desired, said shafts 15 traveling in the slots 9. However, when it is desired to secure the slats 14 in lowered posi-

tion, the hand lever 23 is swung to the position shown in Figure 5 of the drawings. Thus, the rockable shafts 19 are turned in a direction to swing the fingers 20 into the vertical path of the shafts 15, in which position said fingers constitute positive stops for said shafts. When the hand lever 23 is swung to this position, it is locked by the engagement of the bolt 29 behind the hook 28. The locking of the slats 14 in lowered position does not interfere with the tilting of said slats. When it is desired to raise the slats 14, a key, as at 31, is inserted in the lock 30 for retracting the bolt 29 thereby freeing the lever 23 which may now be returned to the position of Figure 4 for swinging the fingers 20 to inoperative position. The slat or slats 14 which carry the shafts 15 are comparatively thick and strong.

It is believed that the many advantages of a window guard constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A window guard of the character described comprising a frame structure for mounting in a window frame, a Venetian blind unit mounted for raising and lowering in said frame structure, vertical guides in the frame structure, shafts on certain of the slats of the Venetian blind unit operable in said guides, and means engageable with said shafts for securing the Venetian blind unit in lowered position.

2. A window guard of the character described comprising a frame structure for mounting in a window frame, a Venetian blind unit mounted for raising and lowering in said frame structure, vertical guides in the frame structure, shafts on certain of the slats of the Venetian blind unit operable in said guides, and means engageable with said shafts for securing the Venetian blind unit in lowered position, said means including vertical shafts journaled in the frame structure, stop fingers on the second-named shafts engage-

able with the first-named shafts, and means for rocking the second-named shafts for swinging the fingers to operative or inoperative position.

3. A window guard of the character described comprising a frame structure for mounting in a window frame, said frame structure comprising a lower portion including a horizontal housing, pairs of vertical guides mounted in the frame structure, a Venetian blind unit mounted for raising and lowering in the frame structure, shafts projecting longitudinally from the ends of certain of the slats of the blind unit and operable between the pairs of guides, rollers on said shafts operable on the guides, rockable shafts journaled vertically in the frame structure, fingers on the second-named shafts engageable with the first-named shafts for releasably securing the blind unit in lowered position, and manually operable means in the housing for rocking the second-named shafts in unison for swinging the fingers to operative or inoperative position.

4. A window guard of the character described comprising a frame structure for mounting in a window frame, said frame structure comprising a lower portion including a horizontal housing, pairs of vertical guides mounted in the frame structure, a Venetian blind unit mounted for raising and lowering in the frame structure, shafts projecting longitudinally from the ends of certain of the slats of the blind unit and operable between the pairs of guides, rollers on said shafts operable on the guides, rockable shafts journaled vertically in the frame structure, fingers on the second-named shafts engageable with the first-named shafts for releasably securing the blind unit in lowered position, and manually operable means in the housing for rocking the second-named shafts in unison for swinging the fingers to operative or inoperative position, said means including arms fixed on the lower end portions of the second-named shafts, a hand lever pivotally mounted in the housing, rods operatively connecting said hand lever to the arms, and means in the housing for locking the lever for securing the fingers in operative position.

MILES S. McDOWELL.
